UNITED STATES PATENT OFFICE

WALTER E. SMITH, OF PROVIDENCE, RHODE ISLAND, ASSIGNOR TO KENNEY MANUFACTURING COMPANY, OF CRANSTON, RHODE ISLAND, A CORPORATION OF RHODE ISLAND

DESIGN FOR A CENTER ORNAMENT FOR DRAPERY RODS OR THE LIKE

Application filed September 7, 1929. Serial No. 32,687. Term of patent 8½ years.

To all whom it may concern:

Be it known that I, WALTER E. SMITH, a citizen of the United States, residing at Providence, in the county of Providence and State of Rhode Island, have invented a new, original, and ornamental Design for Center Ornament for Drapery Rods or the like, of which the following is a specification, reference being had to the accompanying drawing, forming part thereof.

Figure 1 is a face view of a center ornament for drapery rods or the like, showing my new design, and

Figure 2 is an edge view thereof.

I claim:

The ornamental design for a center ornament for drapery rods or the like, as shown.

WALTER E. SMITH.
